LABEL DISPENSER

Carl A. Flood, Framingham, Mass., assignor to
 Dennison Manufacturing Company, Framingham,
 Mass., a corporation of Massachusetts

Application January 2, 1941, Serial No. 372,861

8 Claims. (Cl. 242—55.2)

This invention relates to devices for dispensing labels which are adhesively mounted in a row on one side of an elongate backing strip.

Objects of this invention are to provide improved dispensing devices which are simple and economical in construction, which are efficient and reliable in use, which are easy to load, which extend the labels outwardly from the container and away from the backing strip so that they may be readily grasped for use, and generally to improve devices of the type referred to.

In its principal aspect the present invention involves an apparatus for dispensing labels which are adhesively mounted, with peelable adhesive such as pressure-sensitive or thermoplastic adhesive, in a row on a backing strip divided longitudinally into two ribbons. According to this invention one ribbon is peeled from the successive labels independently of the other ribbon and in the preferred forms of the invention the two ribbons are peeled from the labels successively with the lines of cleavage between the labels and the two ribbons respectively out of alignment with each other. While this can be accomplished in various ways, some of which are disclosed in my copending application Sr. No. 372,862, filed on even date herewith, Patent No. 2,289,642 is issued July 14, 1942, the preferred construction of this application involves edges meeting at an angle, in combination with a pair of rollers or other means for feeding the two ribbons over the edges respectively, thereby to project the labels from the backing at the edges. By arranging the edges so as to intersect each other at an angle substantially at the junction between the two ribbons, the labels are projected from the ribbons as the ribbons are drawn over the edges with far less tendency for the labels to follow the backing around the edges than would be the case if the edges were arranged in alignment with each other.

In a more specific aspect the invention involves a roll of the label strip on the cover of the device and also mounting the feed rollers on the cover, so that the backing ribbons can readily be threaded through the cover and over the feed rollers while the cover is removed from the device. While the cover may be hinged or otherwise removably connected to the device it is preferably arranged to be lifted entirely free of the device for loading and threading purposes.

In another aspect the invention involves a device having space to receive a supply of the label strips and a space to receive the backing strip after it is peeled from the labels, the two spaces

preferably comprising separate compartments, and in the preferred embodiment the compartment for the label roll is in the cover and the compartment for the waste backing ribbons is in the space.

In still another aspect the invention involves feeding the backing ribbons through the cover and along branched paths back into the device, so as to present the labels outside the device and to facilitate separation of the labels from the backing. While the branched paths may come together again, as disclosed for example in said copending application filed on even date herewith, in the preferred embodiment herein disclosed they lead into the waste compartment separately.

For the purpose of illustration a typical embodiment of the invention is shown in the accompanying drawings in which

Fig. 1 is a top plan view of one embodiment;
 Fig. 2 is a section on line 2—2 of Fig. 1;
 Fig. 3 is a section on line 3—3 of Fig. 1;
 Fig. 4 is a section on line 4—4 of Fig. 1;
 Fig. 5 is a detail elevation of one part;
 Fig. 6 is a top plan view of one part of the cover looking down from the line 6—7 of Fig. 2;

Fig. 7 is a bottom plan view of the other part of the cover, looking up from the line 6—7 in Fig. 2 and showing a portion of the cover in section; and

Fig. 8 is a bottom plan view of the label strip shown in Figs. 1 and 2, illustrating how the labels are separated from the backing ribbons.

The particular embodiment of the invention shown in Figs. 1 to 8 comprises a hollow rectangular base 1 having an opening in the top to receive the cover which is formed in two parts 2 and 3 which are preferably composed of Bakelite or other molded material. The part 2 has a depending portion 4 to receive a roll R of label material. As shown in the drawings the label strip comprises two backing ribbons B and B' meeting edge to edge at the line C and a row of circular labels L mounted on the backing ribbons by means of normally tacky adhesive which readily peels from the backing ribbons but which adheres firmly to the labels.

The compartment 4 of the cover is open at the top and partially closing this opening is a guide plate 6 which is mounted on the cover by ears 7 extending through slots 8 of the cover with their hooked ends 9 underlying the top of the cover, together with a stud 11 interengaging with a bayonet slot 12 in the cover. The plate 6 is provided at the sides with overhanging flanges 13

which have extensions 14 near their rearward ends. At the forward end the plate 6 is provided with edges 15 which are inclined to each other so as to intersect substantially at the junction C between the two backing ribbons B and B'. By drawing the two backing ribbons over the edges 15 the labels L are successively projected from the device as illustrated in Fig. 2. As each foremost label is projected from the machine it may be grasped between the thumb and finger and removed from the device. The lateral flanges 13 serve to keep the label strip centered on the plate 6 as the strip feeds along the plate, so that the junction C between the two backing ribbons B and B' is always over the apex of the V-shaped peeling edge 15. To accommodate label strips of different widths, each device may be provided with a set of plates 6 having different widths between the flanges 13, each plate having its ears 7 and stud 11 spaced to fit the device.

The mechanism for feeding each backing ribbon over the edge 15 and into the container 1 comprises a feed roller 21 mounted on a shaft 22 having projecting ends upon one of which is mounted a gear wheel 23. To press the backing ribbon against the feed roller tight enough for feeding purposes the pressure roller 26, mounted in a U-shaped frame 27, presses against the backing ribbon in response to a leaf spring 28 engaging the rear edges of the two legs of the U-shaped frame 27 (Fig. 4). The legs of the U-shaped frame are provided with projections 29 extending into recesses 44 in the part 3 of the cover and the upper end of the frame 27 projects through the top of the cover. Thus by rearward pressure on the projecting upper end of the frame 27 pressure roller 26 may be moved away from the feed roller 21 to facilitate threading the backing ribbons between the rollers. The gears of the two feed rollers are conjointly driven in unison by means of gears 31 fast to a sleeve 32 and a crank 33 extending outside the device to a handle 34. As shown in Fig. 1 the crank 33 carries a pin 35 which engages with any one of a series of hooked recesses in the end of the sleeve 32, the pin being yieldingly held in a recess by a spring 36. Thus the crank can rotate the gears 31 only in one direction, counterclockwise in Fig. 2.

The two parts 2 and 3 of the cover meet at the plane 6-7 (Fig. 2) and they are held together by screws 37 extending through openings 39' in the lower part 3 and threading into recesses 39 in the upper part 2. In their opposed faces the two parts of the cover are provided with recesses to receive the aforesaid mechanism for pulling the two backing ribbons back into the device. For the feed rollers 22 the cover is provided with openings 41 and 41' extending all the way through the parts 2 and 3, these openings having slots 42 and 42' communicating with the outer edges of the parts so that the backing ribbons may be threaded between the rollers 21 and 26 edgewise of the ribbons, thereby avoiding the trouble of pushing the flimsy ribbons endwise between the rollers. The pressure roller assemblies fit into the recesses 43 and 43', the recesses 43' in the lower part 3 being provided with the aforesaid openings 44 to receive the downwardly projecting ears 29 on the frame 27. At each end of each of the openings 41 and 41' the parts 2 and 3 are provided with semi-cylindrical recesses 46 and 46' to fit around the projecting ends of the feed roller shafts 22. The parts 2 and 3 are provided with deeper grooves

47 and 47' to receive the gears 23 and 31. The parts are also provided with semi-cylindrical recesses 48, 48', 49 and 49' to fit around the sleeve 32 and the crank 33 respectively.

5 To load the device of Figs. 1 to 7 the cover is removed from the base and the plate 6 is removed from the cover. After dropping a roll of label material into the compartment 3 the plate 6 is replaced, the label strip is threaded under 10 the overhanging flanges 13 and 14 and the backing ribbons are respectively threaded edgewise through the slots 42 and 42' between the feed and pressure rollers as aforesaid. Then after replacing the cover the device is ready to operate 15 by turning the crank and picking off the labels as they are projected from the device. Ordinarily the crank is turned far enough to project the foremost label almost clear of the backing ribbons, after which the feeding is stopped until 20 the foremost label has been completely peeled from the backing ribbons by hand.

It should be understood that the present disclosure is for the purpose of illustration only and that this invention includes all modifications and 25 equivalents which fall within the scope of the appended claims.

I claim:

1. For dispensing labels from a backing strip longitudinally divided into two ribbons upon 30 which the label material is mounted with peelable adhesive, a device comprising a base, a cover removably mounted on the base, the cover having edges meeting at an angle, means for supporting a roll of the adhesively united label and backing material on the cover, and means for feeding said ribbons from the roll over said edges respectively and thence back into the device, thereby to project the labels from the backing at said edges.

2. For dispensing labels from a backing strip longitudinally divided into two ribbons upon 35 which the label material is mounted with peelable adhesive, a device comprising a base, a cover removably mounted on the base, the cover having edges meeting at an angle, means for supporting a roll of the adhesively united label and backing material on the cover, and a pair of feed rollers mounted on the cover for feeding said ribbons from the roll over said edges respectively and thence back into the device, thereby to project 40 the labels from the backing at said edges.

3. For dispensing sheet material from a backing strip upon which the material is mounted with peelable adhesive, a dispensing device comprising a container for the material, a guide for 45 guiding the material as it feeds from the container, the guide having a wall with an edge over which the strip may be pulled to peel it from the material, the guide extending along one side of the path of the sheet material with a part extending around the edge of the material and thence along the other side, means for guiding the strip in a direction approximately parallel with 50 said wall after it passes over said edge and means for mounting the guide on the container.

65 4. For dispensing sheet material from a backing strip upon which the material is mounted with peelable adhesive, a dispensing device comprising a container for the material, a guide for guiding the material as it feeds from the container, the guide having an edge over which the strip may be pulled to peel it from the material, the guide extending along one side of the path of the sheet material with a part extending around the edge of the material and thence along the other side, 70 means for grinding the strip after it passes over

said edge, and means for detachably mounting the guide on the container so that a pull on said strip tends to hold the guide in place, said last means including interfitting parts which slide into interfitting relation in response to said pull.

5. For dispensing sheet material from a backing strip upon which the material is mounted with peelable adhesive, a dispensing device comprising a container for the material, a guide for guiding the material as it feeds from the container, the guide having an edge over which the strip may be pulled to peel it from the material, the guide extending along one side of the path of the sheet material with a part extending around the edge of the material and thence along the other side, and means for detachably mounting the guide on the container, said means including an integral hook for interengagement with the container so that a pull on said strip tends to hold the guide in place, said hook sliding into engagement with the container in the direction of said pull.

6. In a dispenser for a peelable label strip having a backing which is split into two ribbons, the combination of a container for the strip, a guide for guiding the strip as it feeds from the container, the guide extending along the backing side of the strip and overhanging the other side of the strip, the guide also having a plurality of edges

for peeling said ribbons from the labels, the edges being out of alignment with each other, and means for mounting the guide on the container.

7. In a dispenser for a peelable label strip having a backing which is split into two ribbons, the combination of a container for the strip, a guide for guiding the strip as it feeds from the container, the guide extending along the backing side of the strip and overhanging the other side of the strip, the guide also having a plurality of edges for peeling said ribbons from the labels, the edges being out of alignment with each other, means for drawing the ribbons over the edges respectively, and means for mounting the guide on the container.

8. In a dispenser for a peelable label strip having a backing which is split into two ribbons, the combination of a container for the strip, a guide for guiding the strip as it feeds from the container, the guide extending along the backing side of the strip and overhanging the other side of the strip, the guide also having a plurality of edges for peeling said ribbons from the labels, the edges diverging from each other, means for drawing the ribbons over the edges respectively and thence laterally in opposite directions, and means for mounting the guide on the container.

CARL A. FLOOD.
